UNITED STATES PATENT OFFICE.

JULIUS LAUSCHKE, OF PHILADELPHIA, PENNSYLVANIA.

DESIGN FOR A FIRE-PLACE LINING.

SPECIFICATION forming part of Design No. 15,414, dated September 16, 1884.

Application filed July 21, 1884. Term of patent 14 years.

To all whom it may concern:

Be it known that I, JULIUS LAUSCHKE, a citizen of the United States, and a resident of Philadelphia, Pennsylvania, have invented or produced a new and original Design for a Fire-Place Lining, of which the following is a specification.

My design is fully shown in the accompanying photographic illustrations, Figure 1 representing one of the side plates, and Fig. 2 the back plate, of the lining.

The side plate has at the base ornamentation consisting of a series of Gothic arches. Above the same the plate has side bands—one with geometric ornamentation and the other with decorated panels. Between these bands the ornamentation comprises a lower segmental figure, an upper triangular figure, and intervening ornaments consisting of the representation of a bird, and of leaves, fruit, and flowers. The back plate has a Gothic arch designed on the base, similar to that on the side plates, and at each end of the same a panel decorated as shown. Above the base 25 the plate has opposite side bands, the quad-angular space between which has a diagonal band ornamented with representations of dolphins and dragons, and running from corner to corner of said space, the remaining upper corner having a segmental figure, and the remaining lower corner being crossed by diagonal bands, over which and partly over the central band lies a fan-like ornament.

I claim—

1. In a design for fire-place lining, the side plate consisting of the ornamental figures embodied and grouped substantially as shown and described. 35

2. In a design for fire-place lining, the back plate consisting of the ornamental figures embodied and grouped substantially as shown, and described. 40

In testimony whereof I have signed my name to this specification in the presence of two subscribing witnesses.

JULIUS LAUSCHKE.
